UNITED STATES PATENT OFFICE.

PHILLIP A. MARTINO, OF BOSTON, MASSACHUSETTS, ASSIGNOR TO UNITED LIMB & BRACE CO., INC., OF BOSTON, MASSACHUSETTS, A CORPORATION OF MASSACHUSETTS.

RUBBER-CUSHION SOCKET FOR THIGH LEGS.

Application filed December 21, 1923. Serial No. 682,096.

To all whom it may concern:

Be it known that I, PHILLIP A. MARTINO, a citizen of the United States, and a resident of Boston, in the county of Suffolk 5 and State of Massachusetts, have invented a new and useful Improvement in Rubber-Cushion Sockets for Thigh Legs, of which the following is a specification, reference being had to the accompanying sheet of 10 drawings, forming part thereof.

This invention relates to a cushioned socket for amputated limbs. For the purposes of this application I shall show and describe my invention in its adaptation to 15 the upper socket of an artificial thigh leg, in which relation it is of immediate importance and usefulness. It is to be understood, however, that such treatment is purely illustrative and in no way limiting, 20 and that my invention may be used with any limb socket.

The ordinary limb socket is necessarily stiff and unyielding, and hence uncomfortable to the wearer in direct proportion to 25 the degree of pressure and the extent of bearing thereon. In the case of the upper thigh leg socket, the pressure is mainly on the upper or thigh end of the leg socket where the diameter of the socket is largest 30 and where the bearing area is greatest.

Various pads and linings have been devised for relieving this pressure and for cushioning the bearing, but in the main, such devices have been of temporary, make-shift character, and are open to the objection that they did not adequately cushion the parts; were bulky or uncomfortable in use; and were apt to slip about on the socket. 35

To the end, therefore, of providing a simple and inexpensive device which may be readily applied to a limb socket and which will adequately cushion and wholly relieve the pressure of the contacting parts, I have devised my present invention. In it, the 40 cushion is formed as a moulded bearing surface of relatively soft, flexible cushioning material, as sponge rubber, which not only readily absorbs the pressure of the contacting parts but is self-conforming in character so as to comfortably adjust itself to 45 the shape of the limb to which it is applied; thus providing a smooth and even adapted bearing surface. Moreover, being moulded, the cushion will in use hold its position upon 50 the leg socket and may be adjusted along 55

the entire extent of the limb socket edge, as occasion demands, or interchangeably to either right or left limb sockets.

The construction and manner of using my cushion strip is described and illustrated 60 in the accompanying specification and drawings, throughout which like reference numerals are correspondingly applied, and the characteristic features of novelty are particularly pointed out in the appended 65 claims.

In the drawings:

Fig. 1 is a fragmentary view showing the upper socket of an artificial thigh leg cushioned in accordance with my invention. 70

Fig. 2 is a fragmentary view of the cushioning strip removed.

Fig. 3 is a fragmentary section showing my cushioning strip in applied position, and

Figs. 4 and 5 are similar views illustrating diagrammatically the self-conforming properties of my cushioning strip when adjusted to different positions along the edges 75 of the limb socket.

I have indicated at 1, Figs. 1, 4 and 5, 80 the thigh extremity of an amputated leg, and at 3 the leg stump, which is encased in the upper or thigh socket of an artificial limb or cast 2 of ordinary construction.

According to my invention the upper edge 85 of the socket 2 is cushioned by a moulded cushioning strip of sponge rubber or equivalent cushioning material. This strip is of channel form comprising spaced side walls and a connecting web. The outer wall 4 is 90 an anchoring section, the inner wall 5 is a bearing section and the intermediate thickened connecting web 6 provides the cushioning and pressure-absorbing element proper of the strip, the several parts 4, 5 95 and 6 defining a continuous receiving channel or groove 7 adapted to fit over the upper edge of the socket member 2.

By reason of its channel form, the cushioning strip readily retains its position upon 100 the socket edge and is not apt to accidentally slide therealong in use.

By reason of its capacity for self-conformation, the cushioning and pressure absorbing web 6 of the strip soon comfortably 105 adapts itself to the particular portion of the anatomy with which it is in contact, and hence can be fitted to either side of the thigh extremity, as shown in Figs. 4 and 5, Fig. 4 showing it fitted to the outer and 110

Fig. 5 to the inner side of the thigh extremity, and Fig. 5 also indicating diagrammatically by the dotted lines the self-adapting feature of the strip to the shape 5 of the part being cushioned.

The web 6 is of sufficient thickness to adequately absorb whatever pressure is exerted upon it and at the same time is sufficiently yielding to effectively cushion the parts. 10 The strip itself is long enough to afford ample bearing for the contacting parts, and if desired may be covered with a fine covering of leather or the like, as indicated at 9, Figs. 3, 4 and 5, to increase its comfort. 15 Various modifications in the form, material and uses of my device may be made within the spirit and scope of my invention as defined by the appended claims.

What I therefore claim and desire to secure by Letters Patent is:

1. A cushioning and pressure-absorbing device for a limb socket, consisting of a resiliently self-clamping cushioning strip adapted to slidably fit upon the adjacent 25 end of the limb socket, a portion of said strip constituting a cushioning and pressure-absorbing section and being self-conforming in action so as to adapt itself to the shape of the part of the anatomy with which it contacts according to the position of the strip upon the edge of the limb socket, the resiliency of said strip permitting the walls of said strip to be spread apart and the strip to be adjusted circumferentially along 35 the limb socket edge to any desired position and causing said walls when released to automatically grip the limb socket so as to clamp the strip at the selected position of adjustment thereon.

2. A cushioning and pressure-absorbing device for a limb socket, consisting of a moulded resiliently self-clamping cushioning strip of channel form adapted to slidably receive the adjacent end of the limb 45 socket, a portion of said strip being of thickened cross section and constituting a cushioning and pressure-absorbing section and being self-conforming in action so as to adapt itself to the shape of the part of the anatomy with which it contacts according 50 to the position of the strip upon the edge of

the limb socket, the resiliency of said strip permitting the walls of said strip to be spread apart and the strip to be adjusted circumferentially along the limb socket edge 55 to any desired position and causing said walls when released to automatically grip the limb socket so as to clamp the strip at the selected position of adjustment thereon.

3. A cushioning and pressure-absorbing device for a limb socket, consisting of a moulded resiliently self-clamping cushioning strip of channel form comprising spaced walls and a thickened connecting web defining a continuous channel within which 60 the adjacent end of the limb socket is slidably received, the outer wall of said strip constituting an attaching section, the inner wall constituting a bearing section, and the web constituting a cushioning and pressure-absorbing section and being self-conforming 65 in action so as to adapt itself to the shape of the part of the anatomy with which it contacts according to the position of the strip upon the edge of the limb socket, the 70 resiliency of said strip permitting the walls of said strip to be spread apart and the strip to be adjusted circumferentially along the limb socket edge to any desired position and causing said walls when released to automatically grip the limb socket so as to clamp the strip at the selected position of 75 adjustment thereon.

4. A cushioning and pressure absorbing device for a limb socket, consisting of a 80 continuous moulded rubber strip, generally U-shaped in cross section, and adapted to slidably straddle the adjacent end of the limb socket, the resiliency of said strip permitting the opposite walls of said strip to be 85 spread apart and the strip slide circumferentially along the limb socket end to any desired position of adjustment thereon and causing said walls when released to automatically return towards each other to grip 90 the limb socket therebetween so as to clamp the strip at the selected position of adjustment thereon.

In testimony whereof, I hereunto affix my signature this nineteenth day of December, 1923.

PHILLIP A. MARTINO.
